UNITED STATES PATENT OFFICE.

JOHN OSCAR NEIKIRK, OF MORGAN PARK, ILLINOIS, ASSIGNOR TO NATIONAL DUMP CAR COMPANY, OF CHICAGO, ILLINOIS, A CORPORATION OF MAINE.

DOOR-OPERATING MECHANISM FOR DUMP-CARS.

No. 804,213.

Specification of Letters Patent.

Patented Nov. 17, 1908.

Application filed June 29, 1907. Serial No. 381,449.

To all whom it may concern:

Be it known that I, JOHN OSCAR NEIKIRK, a citizen of the United States, residing at Morgan Park, in the county of Cook and State of Illinois, have invented certain new and useful Improvements in Door-Operating Mechanism for Dump-Cars, of which the following is a specification.

My invention relates in general to dump cars and more particularly to improved door operating mechanism for dump cars of the well-known "National dump car" type, certain embodiments of which are covered by Reissued Patent No. 12,447, W. A. Caswell, February 6, 1906; Patent No. 780,747, Hart & Maltby, January 24, 1905, and Patent No. 833,547, Posson, October 16, 1906.

In the type of dump cars above referred to, it is desirable that means for guiding the reciprocating shaft of the door operating mechanism should be so constructed as not to permit the accumulation of dirt which would interfere with the opening and closing of the doors. It is further desirable that the reciprocating shaft of the door operating mechanism should have a path of movement as far as possible from the inner hinged edges of the doors, in order that the leverage may be such as to minimize the power required to close the doors. It is impracticable to provide guiding means adjacent the outer edges of the doors which will impart to the reciprocating shaft a vertical movement, owing to the truck frames of the car preventing a sufficient travel of the shaft vertically to permit the necessary movement of the doors. While it has heretofore proved impracticable to provide a shaft having a vertical path of movement for closing the doors, yet it is possible, by means of my improvement, to impart to the upright shaft a travel nearer vertical than has heretofore been possible.

The primary object of my invention is to provide, in a dump car of the type referred to, door operating mechanism so constructed as not to permit the accumulation of dirt, thereby insuring the efficient opening and closing of the doors at all times.

A further object of my invention is to provide, in a dump car of the type referred to, door operating mechanism in which the path of movement of the reciprocating shaft will be as far outwardly from the inner edges of the doors and as nearly vertical as

possible, thereby securing the closing of the doors with the least possible expenditure of power.

A still further object of my invention is to provide, in a dump car of the type referred to, door actuating mechanism which will be simple in construction, inexpensive to manufacture and efficient in operation.

My invention will be more fully described hereinafter with reference to the accompanying drawings in which the same is illustrated as embodied in a convenient and practical form, and in which—

Figure 1 is a vertical transverse section through one half of a car, so much of the car structure being only shown as is necessary to disclose my invention; and Fig. 2, an elevational view looking from the right in Fig. 1.

The same reference characters are used to designate the same parts in the two figures of the drawing.

Reference letter A designates one of the longitudinal center sills constituting the central structure of the supporting frame.

a designates a plate which unites the center sill A to other center sills, should more than one center sill be employed.

B indicates one of the transverse members of the supporting frame of the car, such members extending above and being supported by the center structure. The transverse member B may conveniently be formed of a T-shaped cross section, so as to provide a depending web b.

C designates one of the longitudinal side sills of the car which is supported upon the extremities of the transverse members B.

D designates a portion of the longitudinal central portion of the car floor located above the center supporting structure.

E designates a door pivotally connected adjacent its inner edge in any suitable manner to the center structure, as, for instance, by brackets A'. It will, of course, be understood that a plurality of doors E are provided at each side of the longitudinal center structure of the car, so that practically the entire bottom of the car is composed of downwardly swinging doors.

F designates a longitudinal reciprocating shaft extending beneath the door E and adapted through its reciprocation to open and close the door by swinging the same about its pivotal support upon the center

structure. The shaft F is provided with a sprocket wheel f, a plurality of such sprocket wheels being fixed upon the shaft at points intermediate of the adjacent doors. A track is provided for supporting and guiding the shaft F, such track being composed of parallel members g' and g² spaced and supporting transverse studs H. The studs H are preferably provided with sleeves h located intermediate of the members g' and g² of the track. The track is supported in an outwardly and upwardly inclined position in any suitable manner, as for instance, by extending the outer ends of the members g' and g² thereof on opposite sides of the web b of the transverse beam B and securing the same to the web by suitable fastening devices, as, for instance, rivets g.

The lower inner end of the track is supported at a point below the door and between the longitudinal center of the door and its swinging edge by means of braces G' which may conveniently be formed integrally with the members g' and g² of the track. The upper ends of the braces G' are riveted to the web b of the transverse beam B. A seat g² is formed at the upper end of the track by offsetting the same so that the shaft F may be supported thereon when in position to close the door.

K designates a strip extending above and parallel with the track so as to retain the shaft F during its reciprocations in position for the teeth of the sprocket wheel to engage the studs of the track.

E' indicates a strip secured to the under side of the door E, the inner end of which may conveniently form part of the hinge for supporting the door, such strip being provided with a seat e' adapted to rest upon the shaft F when the door is open.

Any suitable means (not shown) may be employed for rotating the shaft F and thereby effecting its reciprocation to open and close the door through the engagement of the sprocket wheel with the track.

The operation of my improvement is as follows: When the door is in the open position shown in Fig. 1, rotary motion applied to the shaft F effects the upward and outward movement thereof to engagement of the teeth of the sprocket wheel with the studs of the track. When the shaft has reached the upper end of its travel, it is supported upon the seat G² of the track and thereby retains the door closed. The door may be opened by imparting a reverse rotary motion to the shaft F sufficient to move the same from the seat G² when it will rotate downwardly by gravity to the lower end of the track, thereby permitting the door to open and the contents of the car to be dumped.

It will be observed that my improved track is in effect a rigid sprocket chain with

which the sprocket wheel on the shaft engages, thereby effecting a positive movement of the shaft and at the same time affording free passageway between the studs of the track for dirt to pass, thereby avoiding the accumulation of dirt in the track which would prevent the proper engagement of the teeth of the sprocket wheel with the track. It will also be observed that in my improved door operating mechanism the track is located beneath the outer portion of the door, thereby resulting in an engagement of the shaft with the door at such a distance from the hinge of the door that the power required to close the door is minimized.

Having now fully described my invention, what I claim as new and desire to secure by Letters Patent, is—

1. In a dump car, the combination with a supporting frame, of a swinging door pivotally supported adjacent its inner edge upon said supporting frame, a reciprocating shaft extending longitudinally beneath and supporting said door, a sprocket wheel fixed upon said shaft, and a track for supporting and guiding said shaft fixed to said supporting frame, said track comprising spaced members upon which the shaft rests and studs supported between the members with which said sprocket wheel engages.

2. In a dump car, the combination with a supporting frame, of a swinging door pivotally supported adjacent its inner edge upon said supporting frame, a reciprocating shaft extending longitudinally beneath and supporting said door, a sprocket wheel fixed upon said shaft, a track for supporting and guiding said shaft fixed to said supporting frame, said track comprising parallel spaced members having a downwardly open space between them, and studs supported between said members and spaced apart distances corresponding to the distances between the teeth of such sprocket wheel.

3. In a dump car, the combination with a supporting frame, of a swinging door pivotally supported adjacent its inner edge upon said frame, a reciprocating shaft extending longitudinally beneath and supporting said door, a sprocket wheel fixed upon said shaft, an upwardly and outwardly inclined track for supporting and guiding said shaft, said track comprising spaced members upon which the shaft rests and studs supported between said members with which said sprocket wheel engages, and means for supporting said track with the lower inner end thereof between the longitudinal center of said door and the swinging edge thereof.

4. In a dump car, the combination with a supporting frame, of a swinging door pivotally supported adjacent its inner edge upon said frame, a reciprocating shaft extending longitudinally beneath and support-

- ing said door, a sprocket wheel fixed upon said shaft, an upwardly and outwardly inclined track for supporting and guiding said shaft, said track comprising spaced members 5 having a downwardly open space between them and studs supported between said members with which said sprocket wheel engages, a hanger depending from the supporting frame for supporting the lower inner 10 end of said track between the longitudinal center of said door and the swinging edge thereof, and means for supporting the upper and outer end of said track.
5. In a dump car, the combination with a 15 supporting frame, of a swinging door pivotally supported adjacent its inner edge upon said supporting frame, a reciprocating shaft extending longitudinally beneath and supporting said door, a sprocket wheel fixed 20 upon said shaft, a track for supporting and guiding said shaft fixed to said supporting frame, said track comprising spaced members and studs supported between the members with which said sprocket wheel engages, 25 and sleeves surrounding said studs intermediate of the members of said track with which the teeth of said sprocket wheel contact.
6. In a dump car, the combination with a 30 supporting frame, of a swinging door pivotally supported adjacent its inner edge upon said supporting frame, a reciprocating shaft extending longitudinally beneath and supporting said door, a sprocket wheel fixed 35 upon said shaft, and a track for supporting and guiding said shaft fixed to said supporting frame, said track comprising spaced members upon which the shaft rests and studs supported between the members with 40 which said sprocket wheel engages, said track being offset to form a seat at its upper and outer end to support said shaft when in position to close said door.
7. In a dump car, the combination with a 45 supporting frame, of a swinging door pivotally supported adjacent its inner edge upon said supporting frame, a reciprocating shaft extending longitudinally beneath and supporting said door, a sprocket wheel fixed 50 upon said shaft, a track for supporting and guiding said shaft fixed to said supporting frame, said track comprising spaced members and studs supported between the members with which said sprocket wheel engages,
- and a guide strip secured beneath said door 55 and having a seat formed therein to rest upon said shaft when said door is open.
8. In a dump car, the combination with a supporting frame, of a swinging door pivotally supported adjacent its inner edge upon 60 said frame, a reciprocating shaft extending longitudinally beneath and supporting said door, a sprocket wheel fixed upon said shaft, a track for supporting and guiding said shaft, said track comprising parallel spaced 65 members and studs between said members, sleeves surrounding said studs with which the teeth of said sprocket wheel engage, a hanger depending from the supporting frame formed integrally with said track and 70 supporting the lower inner end thereof between the longitudinal center of said door and its swinging edge, said track having a seat at its upper and outer end to support said shaft when the door is closed, and a 75 guide strip secured beneath said door and having a seat formed therein to rest upon said shaft when the door is open.
9. A railway car having a flat floor comprising longitudinally arranged dumping doors and a supporting framework, a reciprocating shaft supported by the framework of the car beneath the doors and engaging the doors between their longitudinal centers and outer swinging edges for supporting and 85 operating the doors, upwardly and outwardly inclined sprocket tracks comprising spaced members upon which the shaft is carried and studs between said members, and sprocket wheels on the shaft engaging the 90 tracks.
10. A railway car having a flat floor comprising longitudinally arranged dumping doors and a supporting framework, a reciprocating shaft supported by the framework 95 of the car beneath the doors and engaging the doors between their longitudinal centers and outer swinging edges for supporting and operating the doors, upwardly and outwardly inclined tracks upon which the shaft 100 is carried, sprocket wheels on the shaft engaging the track, and means for keeping the shaft in engagement with the tracks.
